UNITED STATES PATENT OFFICE.

CHARLES J. ANDERSON, OF MELROSE, OREGON.

CAMP-BED.

1,198,310.

Specification of Letters Patent. Patented Sept. 12, 1916.

Application filed November 30, 1915. Serial No. 64,256.

To all whom it may concern:

Be it known that I, CHARLES J. ANDERSON, a citizen of the United States, and a resident of Melrose, in the county of Douglas, and 5 State of Oregon, have invented certain new and useful Improvements in Camp-Beds, of which the following is a specification.

My invention is an improvement in camp beds, and the invention has for its object to 10 provide a bed of the character specified, in connection with a suitable tent, wherein a framework is provided for supporting the tent covering, and wherein the bed is supported by the frame and is adjustable with 15 respect thereto, to compensate for inequalities in the ground, and to permit the bed to be raised and lowered.

A further object is to provide a supporting framework for the tent, and for the bed 20 so arranged that it may be folded, and packed into small compass for transportation.

A further object is to so arrange the connection between the supporting frame and 25 the bed that the bed may be level, regardless of the position of the tent.

In the drawings: Figure 1 is a perspective view of the camp bed; Fig. 2 is a transverse section; Fig. 3 is an enlarged detail of the 30 upper portion of Fig. 2; Fig. 4 is a section on the line 4—4 of Fig. 3; Fig. 5 is a detail of the lower end of one of the supporting standards; Fig. 6 is a longitudinal vertical section through the camp bed; Fig. 7 is a 35 diagrammatic view showing the parts in another position; Fig. 8 is an enlarged detail of a portion of the bed; and Fig. 9 is a sectional view of a modified construction.

In the embodiment of the invention shown 40 in Figs. 1 to 7, the tent frame is composed of a ridge pole consisting of similar sections 1 and 2, hinged together at their meeting ends by a hinge connection 3 which is on the under side of the sections, so that the joint between 45 the sections may be moved upward to fold the sections upon each other, but may not move downward beyond the point where the sections are in alinement. The joint is in fact a species of rule joint. Two pairs of 50 standards are provided for supporting the ridge pole, a front and a rear pair, and each standard consists of three sections, namely, an upper section 5, an intermediate section 6, and a lower section or stake 7. The sections 5 and 6 of each upright or standard are hinged together as indicated at 8, by a hinge

similar to the hinge 3, and similarly arranged with respect to the sections. The section 7 of each upright or standard is of channel material, and the lower end of the section 6 of each standard is received within the upper end of the adjacent stake, between the side walls thereof, as shown more particularly in Fig. 5. A bolt 10 is passed transversely of the side walls of the stake, and of 60 the section 6, and another bolt 11 is passed through the section and through the body of the stake, each bolt being engaged by a suitable nut on the opposite side from the head. Thus each stake is rigidly secured to 65 the lower section of the adjacent standard, and it will be noted that the outer corner of each lower section is beveled as shown at 12, and that this beveled surface bears against the body of the stake in such manner that 70 the section 6 is inclined at an obtuse angle with respect to the section or stake 7. The upper inner corners of the upper sections 5 of the members of each pair of standards are beveled as indicated at 13, at such an 75 angle that when the beveled surfaces are superposed or abutted, the standards diverge outwardly and downwardly away from each other, as shown in Figs. 2 and 3. The abutting upper ends of the upper sections of 80 each pair of standards are held together by a clamping ring 14 of metal or the like, which encircles the abutted upper ends, resting in the notches or grooves 15 in the 85 outer faces of the sections, as shown in Fig. 90 3. Each pair of standards is secured to the adjacent section of the ridge pole 1 or 2, as the case may be, by means of a pin 16, which is passed upward through registering 90 grooves in the abutting beveled corners of 95 the upper sections of the standards, and through a registering opening in the ridge pole. Each of the pins 16 is held in position by the pressure of the section on the pin, and the openings in the ridge pole section 100 for receiving the pins 16, are spaced apart from the adjacent ends of the ridge pole sections.

It will be noted that each section of the ridge pole is provided with two openings, 105 17 and 18, respectively, for receiving the adjacent pin 16. One of these openings, 17 in the present instance, is exactly vertical, so that when the pin 16 is engaged with the opening the standards or uprights will be 110 vertical. When the pin 16 is engaged with the opening 18 of the ridge pole, the stand-

ards will take an inclined position, as indicated in dotted lines in Fig. 6. The standards and the ridge pole are arranged as shown in Fig. 6, the stakes 7 being driven 5 into the ground, and the upper end 19 of each stake provides a driving surface for permitting the stake to be driven into the ground.

The covering for the framework, of duck, 10 canvas, or like suitable material, consists of an inclined wall 20 forming a roof, and side wall at one side of the tent, and a roof portion 21, at the opposite side. The portions 20 and 21 are integral and they have flies or 15 flaps 22 and 23, respectively, at their ends, the said flaps or flies being adapted to be closed as shown in Fig. 2, to close the ends of the tent. The side wall 20 extends from the ridge pole outwardly and downwardly, 20 approximately parallel with the adjacent standards, and the said side wall is guyed or anchored at its lower side edge by means of a series of pegs or stakes 24. The lower edge of the side wall 20 is provided with 25 openings which are engaged by loops 25 on the ends of ropes or cords 26. These cords or ropes 26 are connected to the stakes 24, the said stakes having the usual notches 27 for preventing slipping of the cords. 30 The side wall 21 of the tent covering is inclined at a more acute angle with respect to the ground, and the said wall is also inclined at an acute angle with respect to the adjacent standards 5-6-7. The free lower 35 edge of the wall 21 is provided with a series of openings, for receiving loops 28 on the ends of guy ropes 29. These ropes extend outwardly in the plane of the side wall to a connection with the tent pegs or stakes 40 30, the said pegs or stakes being arranged at intervals corresponding to the intervals of the guy rope 29. A side wall 31 depends from the under face of the wall 21, near its free edge, and the lower edge of the side wall 31 is provided with guy ropes or cords 45 32, which are secured to stakes or tent pegs 33. The flies 22 and 23 at each end may be secured to pegs or stakes 34 when the said flaps or flies are closed, and holding strips 50 35 are provided at the edges of the side walls 20 and 21, for holding the flaps or flies 22 and 23 rolled back, as shown at the left of Fig. 1 of the drawing. At each side, the ridge pole and the supporting frame are guyed by the wall 20 of the tent, 55 and at the other side the guy ropes 29 are provided, the said ropes being connected at their upper ends to the wall 21, and at their lower ends to the stakes 30 before mentioned. 60 The bed is in the form of a strip or sheet 37, of canvas, duck or other suitable material, having each of its ends turned over upon the body of the strip and secured thereto, to form a tubular structure 38 at 65 each end of the strip. Supporting bars 39

are passed through the tubular structures 38, and these bars 39 are arranged to be supported by the pairs of standards. For this purpose the section 6 of each standard is provided near the stake 7 with a series of 70 laterally extending vertically spaced pins 40. The pins are on the outer faces of the standard sections, and they are spaced apart from each other in such manner that the bars 39 may rest upon the pins. The pins 75 of each standard section are in register with the pins of the other standard section of the pair, and also with the pins of the adjacent standard of the other pair. The stakes 7 provide an efficient anchorage for the lower 80 ends of the standards, and the pins 16 provide an anchorage for the tops of the standards. When for instance the tent is arranged on an incline, as shown in Fig. 7, with one pair of standards 41 at a lower level 85 than the other pair 42, the supporting bars 43 for the strip 44 may be engaged with different pins 45 at the respective standards, to support the strip 44 in approximately horizontal position. 90

The ridge pole 46 in the above construction is inclined to correspond with the inclination of the ground, and that supporting bar 43 of the bed at the lowest pair of standards 41 is supported on the uppermost 95 pins, while that supporting bar at the opposite end is supported on the lowermost pins. Thus the canvas is held approximately horizontal.

It is obvious that if it is desired to incline 100 the bed from the head downward, one end may be lowered from the position shown in Fig. 6 for this purpose. When not in use the strip 37 may be pushed to one side, that is, toward the wall 20 or toward the wall 21, as shown in Fig. 1, and the interior of the tent is thus left free and unobstructed. It is obvious that the entire bed structure might be removed if desired. If it is desired to provide more slack in the strip 37, 110 the pin 16 may be released from the opening 17, to permit the upper ends of the standards to swing inwardly into the dotted line position of Fig. 6, and the pins will then be engaged with the openings 18. It 115 is obvious that were the tent inclined from side to side, instead of from end to end, the bed might yet be arranged level, by engaging the ends of the bars with pins that were 120 on a level.

In Fig. 9 a modified construction is shown, wherein the lower sections 47 of the standards are secured, to the stakes 48, by means of bolts 49, which are passed through the lower ends of the standards and through the bodies of the stakes. The outer corner of the standard section is beveled as indicated at 50, in the same manner as in the form shown in Figs. 1 and 2, so that when this beveled surface abuts the body of the stake, 125 130

the standard will be inclined with respect to the stake. Each standard section 47 is provided with a series of tapering or conical openings 51, and the supporting bars 52 for the strip 53 have reduced conical stems 54 for engaging these openings 51. When the tent is not in use, the covering may be removed and folded, after which the framework, consisting of the ridge pole and the standards, may be detached, and the sections of the ridge pole and the sections of each standard may be folded upon each other into a compact bundle. In practice, no single section will be of greater length than may be conveniently carried in a vehicle.

I claim:

1. A device of the character specified, comprising a supporting frame consisting of a plurality of pairs of standards, the members of each pair converging toward their upper ends, a ridge pole resting on the upper ends of the pairs of standards, a bed comprising a sheet of fabric material having a tubular portion at each end, a supporting bar extending through each of the tubular portions, a series of means on each pair of standards at the outer sides thereof for supporting the supporting bars, said supporting means being spaced vertically from each other, the ridge pole having near each end a vertical opening, and the abutting portions of each pair of standards having registering grooves forming a passage adapted to register with an opening at the adjacent end of the ridge pole, a pin passing through the grooves and one of the

openings, and a clamping loop encircling the abutted ends of each pair of standards.

2. A device of the character specified, 40 comprising a supporting frame consisting of a plurality of pairs of standards and a ridge pole, the members of each pair of standards converging toward their upper ends, a metal pointed stake connected with 45 the lower end of each standard, each stake being of channel material and comprising a body and approximately parallel side walls, the side walls being beveled toward the lower end of the stake, and the lower 50 end of the standard being received in the upper end of the stake between the side walls, said lower end being beveled at the top of the stake to constrain the stake to extend at an obtuse angle with respect to 55 the standard, the upper end of the stake forming a driving surface.

3. A device of the character specified comprising a supporting frame consisting of a plurality of pairs of standards, the 60 members of each pair converging toward their upper ends, and a rigid connection between said upper ends, a bed comprising a sheet of fabric material having at each end a tubular portion, a supporting bar extending through each of the said portions, and a series of laterally extending pins on each standard for engagement by the extended ends of the adjacent bar, said pins being spaced apart from each other.
